UNITED STATES PATENT OFFICE.

JACOB T. WAINWRIGHT, OF PITTSBURG, PENNSYLVANIA.

METHOD OF WORKING HEAT-REGENERATORS.

SPECIFICATION forming part of Letters Patent No. 483,752, dated October 4, 1892.

Application filed August 28, 1888. Serial No. 284,036. (No model.)

To all whom it may concern:

Be it known that I, JACOB T. WAINWRIGHT, of Pittsburg, Pennsylvania, have invented a new and useful Improvement in the Method 5 of Working Heat-Regenerators, of which the following is a full, clear, and exact description.

In the accompanying drawings I show apparatus embodying my invention, and shall describe the invention with reference thereto, 10 premising, however, that the apparatus is susceptible of modification in divers ways in form and construction, as will be understood by those skilled in the art.

Figure 1 of the drawings shows the apparatus in section, that part above the floor-line being in vertical section and the part below the floor-line being in horizontal section. Figs. 2 and 3 are views of modified forms of apparatus embodying the invention.

Like symbols of reference indicate like parts in each.

My invention has relation to the art of operating regenerative hot-blast stoves in connection with metallurgical furnaces, and has 25 its special application, in connection with the use of the cheaper grades of gas-fuel, in reducing, melting, and heating furnaces.

Attempts which have heretofore been made in the application of fuel-gas for this use 30 have not been satisfactory because of insufficiency of temperature maintained in the furnace when the mixture of fuel-gas and air in the furnace-blast is regulated to produce a neutral or reducing action. The cause of 35 this defect has been due to the inefficiency of the apparatus employed.

In order to maintain the requisite high temperature in the furnace, it is necessary that the gases introduced thereto should be 40 highly preheated, since otherwise the proper temperature cannot be obtained by the limited combustion permitted in the furnace. The reason for limiting this combustion is to prevent an oxidizing effect upon the furnace-

45 contents. In order to effect this preheating of the furnace-gases by the apparatus shown in the accompanying drawings, I use alternately-acting regenerative chambers, each divided into two separate passages. These 50 chambers having been heated, I pass the air and gas separately through the passages of

one of them, so as to raise these gases to a high temperature, mingle the heated air and fuel-gas on their exit from the regenerator, so as to augment their heat by partial combustion, pass a portion of the partially-consumed fuel-gas through the reducing-furnace, and conduct the residue to the second regenerator, where it passes through one of the regenerator-passages together with heated air, which 60 has been passed through the other passage, thus producing intense heat and quickly raising the regenerator to the necessary temperature. The heating of the gaseous fuel (by which I mean gas and air or gas alone) which is thus 65 effected is very thorough, and the extra mechanical energy required to produce the necessary blast-pressure is more than compensated by the additional increase of temperature due to the better heating of the regenerators and the better combustion of the fuel under greater pressure. It should be noted that 70 although in the specification and drawings I describe the preheating of both fuel-gas and air, yet in some cases the fuel-gas alone may 75 be passed through the first regenerator. This may be so in case the fuel-gas contains considerable oxygen. The operation of the second regenerator, however, would be the same whether air be preheated or not in the first 80 regenerator.

In the accompanying drawings, S represents the vertical shaft of a reducing-furnace, having at its base an open hearth H, which is connected with the furnace-shaft by a passage 85 or flue h. This furnace and hearth may be of any suitable construction, since the mechanical details thereof do not form essential features of limitation of my present invention. The hearth H has a tap-hole h⁴ and may be 90 provided with a removable bottom h², mounted on bottom plates h³. The furnace S is preferably contracted near the base and may be provided with ordinary water-cooled bosh-plates S'. 95

L R are hot-blast stoves set at opposite ends of the hearth H and connected therewith by neck-flues l r. The walls of the stove may be provided with inclosing air-spaces M, and each stove is divided into two or more checker-work-filled passes or flues n o n' o' by a partition-wall p.

q is a cold-air flue controlled by a damper A and connected by flues q' q^2 with the flues o o' of the stoves.

V is a valve controlling the flues q' q^2 , as 5 shown.

s is a fuel-gas inlet controlled by a damper G.

t t' are flues leading to the flues n n' of the stoves.

T is a valve controlling the flues t t' .

U is a second cold-air inlet controlled by a damper u.

W is a stack-flue controlled by a damper F, and w is a valve arranged as shown in the drawings.

15 I shall now describe the operation of the apparatus as thus constructed. The furnace S being charged with ore and the proper proportion of flux and solid fuel, the gaseous reducing-fuel is supplied thereto in the following

20 manner: A blast of cold air is passed continuously through the flue q and by means of the valve V is diverted into one of the flues q' q^2 . In the drawings this valve is shown in position to cause the passage of the air through the 25 flue q' into the flue o of the stove L. Fuel-gas is also admitted from the flue s and passes into the flue t or t' , according to the position of the valve T, and thence to the flue n of the stove L. As shown in the drawings, the valve

30 T is set so as to cause the passage of the gas into the flue t . The valve w is shown in the drawings in proper position to connect the chimney-flue W with the flue t' and the cold-air inlet U with the flue q^2 . When the

35 parts are in these positions, the fuel-gas and air from the flues t and q' pass up through the flues n o , which have been previously heated by combustion of fuel-gas therein, and having been heated in their passage they

40 mingle in the combustion-chamber X. The quantity of air admitted is so regulated by the damper A in proportion to the volume of fuel-gas that when the air and fuel-gas mingle only a partial combustion ensues. From

45 the combustion-chamber X the burning and superheated gases pass through the flue l over the hearth H. A portion of the gases passes upwardly through the flue h into the reducing-furnace and through the stock therein.

50 The remainder passes on through the flue r into the chamber X', where it meets an incoming current of air passing up through the previously-heated flue o' of the stove R. The fuel-gas and air unite and in a state of combustion pass down through the flue n' and

55 thence through the flue t' to the chimney-flue W, thus heating said regenerator-flue to a high degree, the upper part, however, being heated more than the lower part and the best conditions for effective work being thus secured.

The proportion of fuel-gas which passes through the stove R, instead of passing through the reducing-furnace, is determined by the extent of opening of the damper F.

60 If this damper be wide open, a large proportion of the gas will be diverted from the re-

65 ducing-furnace and caused to pass through the stove; but if the damper be partially closed the resistance offered to the passage of the fuel-gas through this stove will be such 70 as to cause a greater proportion of the fuel-gas to pass through the reducing-furnace.

The course of the fuel-gas and air through the flues of the stove R may be reversed from time to time by shifting the valve w, so as to 75 connect the flue n' with the cold-air inlet U and the flue o' with the chimney-flue W.

When the stove L has become cooled, so as to no longer heat the passing gases to the requisite high temperature, the valves V and 80 T may be shifted into position, so as to cause the fuel-gas and air to pass up through the flues of the stove R and the outgoing partially-consumed fuel-gas to pass down through one of the flues of the stove L, in which it is 85 burned with air from one of the other flues of said stove. The valves are thus manipulated as often as may be necessary during the working of the apparatus, and uniform results are best secured by regularity and frequency in 90 their reversal. By these operations the gas admitted to the reducing-furnace is preheated to a high temperature by the stove through which it passes, its heat being augmented by partial combustion before it enters the reducing-furnace, and the stoves are alternately heated to a high degree by the means and mode of operation which I have just described.

The conditions of the gases in the flues l and r may be observed by providing small gas-jet 95 outlets b b'. The proportion of air to the combustible gas may be judged by observing the burning jets from these outlets, and the proportions may be maintained in proper relation to each other to produce the proper reducing action in the furnace by manipulating the valves A and G. From the above description it will be seen that I am enabled to regulate the mixture of gases that enter the furnace, so as to produce any desired degree of reducing power, and at the same time the mixture of the preheated fuel-gases for reheating the regenerative material can be regulated so as to produce complete and efficient combustion without interfering with the gases that pass 105 into the reducing-furnace.

I am aware that Siemens and others have arranged regenerative stoves in connection with a metallurgic furnace whereby preheated gases are caused to pass into the furnace; 110 but it has not heretofore been proposed to reheat these stoves with gases resulting from combustion, in which gases are introduced that have been preheated in the regenerative material but are diverted from the blast passing 115 into the furnace.

The scope of my invention is not limited to the use of any particular type of furnace or kind of fuel, as the ordinary open-hearth furnace would be preferable for certain operations. Thus in Fig. 2 I show the use of the 120 stoves in connection with an open-hearth fur-

nace H', through which the gases pass directly from one regenerative stove to the other. Neither is it necessary to maintain a reversing action through the furnace, since the stoves may be connected by means of a flue in which this action is maintained, and the furnace may be connected to this flue by means of a separate blast-flue. Thus in Fig. 3 I show such apparatus in which the combustion-chambers X X' are connected by a flue X², and from this flue a branch flue X³ leads to the hearth of the metallurgical furnace. In operation of the apparatus shown in this figure part of the gas passes directly through the flue X² from one stove to the other, and a portion is diverted through the flue X³ to the furnace, the relative volumes of the currents depending on the setting of the valves; also, the regenerative material may be separated into any convenient arrangement and number of parts or chambers, whereby the furnace-blast may not be contaminated

with any gas that it is desired to use for re-heating the stove.

I claim—

The method of working regenerators, consisting in heating a single surface regenerator by passing products of combustion therethrough, then reversing the current and passing a gas in an opposite direction therethrough, passing through a second preheated regenerator or set of regenerators another gas or gases capable of producing combustion when united therewith, uniting these gases and passing the mixture through a third regenerator or set of regenerators, and reversing the currents through the second and third regenerators while they continue in the same direction through the first regenerator, substantially as and for the purposes described.

JACOB T. WAINWRIGHT.
